(57) **CLAIM**

I claim the ornamental design for a battery, as shown and described.

DESCRIPTION

FIG. 1 is a front top perspective view of a battery, showing the new design.

FIG. 2 is the front view thereof;

FIG. 3 is the rear view thereof;

FIG. 4 is the left-side view thereof;

FIG. 5 is the right-side view thereof;

FIG. 6 is the top view thereof; and,

FIG. 7 is the bottom view thereof.

1 Claim, 7 Drawing Sheets

FIG. 1

FIG. 2

FIG. 3

FIG. 4

FIG. 5

FIG. 6

FIG. 7
